UNITED STATES PATENT OFFICE.

WINFIELD E. HINSDALE, OF TRENTON, NEW JERSEY.

WATER-CLOSET.

1,391,476.

Specification of Letters Patent. Patented Sept. 20, 1921.

Application filed June 4, 1920. Serial No. 386,505.

To all whom it may concern:

Be it known that I, WINFIELD E. HINSDALE, a citizen of the United States, residing at Trenton, in the county of Mercer and State of New Jersey, have invented certain new and useful Improvements in Water-Closets, of which the following is a specification.

My present invention pertains to improvements in water-closets, and more especially to closets of the siphon jet type.

The invention is directed particularly to improvements in existing types of siphon jet water-closets, and has for one of its objects the incorporation, integrally with the bowl and general closet structure, of a vent duct of large area and, at the same time, to retain a symmetrical shape and to avoid distortion of the complete closet by the incorporated chambers and water-ways or passages.

In designing such a structure, it should be borne in mind that certain features in common use, such as the means provided for attaching the seat, have become more or less staple or standardized, and the fact that makers of special seats have adopted certain and fixed measurements makes it imperative that such a design conform to the trade requirements in order to obviate the necessity of providing special trimmings and consequently enhancing the cost thereof.

Furthermore, it is desirable, if in fact not necessary, that little, if any, departure be made from what has grown, by years of use and the practice of all makers, to be the standard measurement of a closet, both as to height and width.

A still further object of the invention resides in the provision of special ways for the introduction of the water into the flushing rim and to the jet opening; also in the provision of special water ducts or openings for flushing the walls of the vent duct.

The arrangement of the channels or conduits which convey the water to the flushing rim is such that all the contained air in the water passages or conduits above the water-level in the bowl will be driven ahead of the falling water from the flushing device, without in any way mixing said confined air with the following or advancing water, thus eliminating all noise caused by the mixing of air and water under pressure.

It is evident from what has been said that in order to bring about the introduction of a

vent duct and the necessary water ways or channels within the confines of a standard closet, changes must be made in the water ways, both as to inlet and outlet, and that the vent duct itself must be kept below the plane of the rim of the bowl until well clear of the portion of the closet that is intimate to the user.

Two embodiments of the invention are disclosed in the annexed drawings where-

in,

Fig. 1 a vertical longitudinal sectional view of the closet having a local or rear vent of large area;

Fig. 2 a transverse vertical sectional view,

the plane of the section at the left being

taken on the line I—I and that to the right

being taken on the line II—II of Fig. 1;

Fig. 3 a sectional plan view, the section

being taken on the line III—III of Fig. 1;

Fig. 4 a transverse vertical sectional view

taken on the line IV—IV of Fig. 1;

Fig. 5 a vertical longitudinal section of a

closet embodying the invention but omitting

the local vent.

Referring first to Figs. 1 to 4 inclusive, it will be seen that the closet is formed as a one-piece structure, with the various ducts

and water-ways therein.

The bowl proper is denoted generally by

1, and surmounts a base or pedestal 2. The

vent duct is designated by 3, the inner por-

tion whereof opens directly into the bowl

and under the diminished rear segment of

the flushing rim 5. Said rim, as will be

noted on reference to Figs. 1 and 3, (see also

Fig. 5) is continuous in its oval. The regu-

lar closet of standard manufacture and with-

in the accepted space measures allowed, car-

ries an inside oval, as to the bowl rim, of

12 inches for its long diameter.

To secure anti-soiling features to the rim

it has heretofore been deemed necessary to

distort the oval and abruptly enlarge the

rear section of the oval by receding same in

a semi-squared portion of lesser or greater

width in order to not disturb the usual

method of feeding the rim from the rear.

In other cases the rim oval has been car-

ried back for one inch to a point in order

that the usual rim feed would have water

way of sufficient capacity. Other methods

of receding the rim, such as raising same

above the regular plane of the top and un-

dercutting same, have been used, but in all

105

cases the regularity of the rim has been destroyed and the maximum of non-soil not achieved.

By my method of construction I have secured a true oval to the rear on a long diameter of 13 inches—thus, with the seat attachment remaining fixed, I have removed the entire rim one inch to the rear and receiving thereby the maximum non-soil angle across 10 the edge of the seat opening and flushing rim. This idea is not broadly claimed herein as the same forms the subject matter of my copending application Serial No. 181,069 filed on or about the 17th day of July 1920.

15 To the rear of the seat hinge-post holes 7, duct 3 extends upwardly and rearwardly, terminating in a mouth or spigot 8. Pockets 9 are provided in the side walls of the closet, or the vent duct, beneath the holes 7, which 20 pockets, while enlarging the vent duct, also afford a ready means for securing the nuts upon the inner ends of the seat hinge-posts. Furthermore, the retaining nuts will be inclosed, thus eliminating the usual and unsightly bolts and nuts as they appear under 25 the regular exposed seat wings of the standard closet of today.

It will thus be seen that I have provided a 30 vent duct of maximum area, and one which is open and free throughout its length between the bowl and the stack to which it is connected. Such an arrangement of the vent duct, and the reconstruction of the rear portion of the flushing rim 5 necessitates a re- 35 arrangement of the water ducts and passageways.

The water supply from the usual tank or reservoir enters the regular top inlet or conduit 10 from which extend branches or ways 40 11, which pass downwardly and slightly forward and open inwardly into a chamber or recess 12 underlying the bottom of the trap and provided with the usual jet orifice or opening 13. Each of the vertically-disposed ways 11 is in communication with a horizontally disposed way 14, the forward end of which turns upwardly, as at 15, and opens into the adjacent flushing rim from below at a point on either side of the closet 50 just forward of a rear segment of the rim oval containing the diminished water way shown by Figs. 1 and 3 and made necessary by my construction to secure the full oval rim within allowed space.

55 A plurality of openings 16 will preferably be provided through the wall between the upper portion of the vent 3, and the conduit 10, to thoroughly flush or wash down the walls of the vent duct at each operation 60 of the closet.

The trap and siphon outlet of the closet are denoted by 17 and 18, which latter terminates in the usual outlet nozzle 19.

From the foregoing it is thought that 65 the advantages accruing from the construc-

tion will appear to those skilled in the art, but it may be well to set them forth in a general way.

Heretofore, vent ducts have been made integral with the closet and connected to 70 the bowl by means of one or more openings extending through the bowl wall and under the edge of the continuous flushing rim, producing an uncleanable pocket back of the bowl surface and out of reach of the flush- 75 ing water.

With the construction above set forth I am enabled to provide a local or rear vent which has a clear and free opening extending from the bowl to the stack and which in 80 a closet of standard dimensions may be of full four-inch diameter. Furthermore, the duct is kept below the rim of the closet bowl until well beyond the point of seat attachment, thus taking the rear raised portion of the vent well out of the way of the user.

Also, by reason of the placing of the bowl outlet passage or trap farther to the rear than usual, I secure a greater volume of 90 water in the bowl and trap and a proportionally greater resistance to the passage of sewer gas.

When no local vent exists or is needed, the vent duct may be omitted, and the other 95 structural features and their inherent advantages retained. Such a construction is disclosed in Fig. 5 and inasmuch as the vent duct is alone omitted the other parts are denoted by the same reference numerals as in 100 the other figures.

The receded full oval sanitary rim, the covered seat post boxes or pockets, and the above water-level feed to the rear ends of the flushing rim are all present. The receded rear portion of the bowl surface, denoted by 20, which extends up to the pockets or boxes 9, is washed down by the water passing from the openings 16, as under the other construction.

110 While the design of a closet around the novel features which I have introduced seemingly admits of but little change, still it is evident that closets of types other than of the siphon jet class may be similarly produced, and I do not, therefore, wish to be understood as limiting myself thereto.

115 What is claimed is:

1. In a water closet, the combination of a bowl; a flushing rim therefor; a vent duct 120 opening into the bowl underneath the rim; and a pocket opening toward the vent passage and reached from the interior of the bowl through the duct, formed in each of the side walls of the duct; the upper walls 125 of each pocket having an opening therein for the reception of the seat hinge post.

2. In a water closet, the combination of a bowl; a flushing rim fed from below on either side of the bowl from horizontal water 130

- ways integral with the closet structure and entirely above the water level in the bowl, but entirely below the flushing rim; a vent duct of large area disposed between the outlet 5 trapway of the bowl and the flushing rim and its rearward extension, forward of the point of seat attachment, but rising through said rearward extension with its terminal entirely above the same; means for 10 flushing the interior of said duct and pockets on either side of said vent duct, closed as to outside appearance to receive seat attaching means through perforations in the top of said pockets.
- 15 3. In a water closet, the combination of a bowl; a continuous flushing rim; a seat attaching means to the rear of the bowl, wholly inside the outer walls of the closet structure, perforated from the top only to receive hinge locking means and accessible 20 through a receded adjacent portion of the closet bowl; a vent duct originating in the bowl under the flushing rim and terminating at the extreme rear of the closet entirely 25 above the top of the flushing rim with no part of the vent duct structure above the rim of the bowl forward of the point of seat attachment; and means for wasing the inner surface of the vent duct.
- 30 4. In a water closet, the combination of a bowl; a continuous flushing rim therefor; an inlet above the trap section and opening into a water chamber, located adjacent the trap through conduits on either side of the 35 closet leading from said inlet, said water chamber being provided with a jet opening; and a horizontal conduit on either side of the closet wholly below the flushing rim and above the normal water level leading from 40 the conduits aforesaid to the flushing rim and feeding the same from below at a point forward of a rear segment of the rim.
5. In a water closet, the combination of a trap; a continuous flushing rim diminished 45 in its rear segment and fed from below at a point on either side forward of the diminished segment; horizontal water ways integral with the closet structure and entirely below the rim section and above the water 50 level in the bowl, said horizontal ways opening into the flushing rim; an actuating jet chamber; a pair of main water passages opening into said chamber and into the horizontal water ways; a large vent duct originating 55 in the rear of the bowl below the diminished section of the rim and passing over the trap way underlying the extension of the top of the closet beyond the rim forward of the point of seat attachment and rising 60 through said extension and terminating at its end entirely above the plane of the closet; and means for washing the inner surfaces of said vent duct.
6. In a water closet, the combination of a bowl; a continuous flushing rim diminished 65 at its rear section; a vent duct extending rearwardly from the bowl and opening into same below the diminished section of the rim, said duct forward of the point of seat attachment lying entirely below the upper 70 plane of the bowl and entirely above the plane of the bowl rim at its outlet end; a series of water jets opening into the upper portion of the duct; and water conduits entirely above the water level in the bowl, on 75 either side of the bowl and leading horizontally to the flushing rim and opening into same from below.
7. In a water closet, the combination of a bowl; a continuous flushing rim fed from below its own level, on either side of the closet, through horizontally disposed water passages integral with the closet structure and entirely above the water level in the bowl; main water passages communicating with 80 the horizontally disposed passages aforesaid, a jet chamber provided with a jet orifice in communication with said main water passages; a local vent duct originating in the bowl entirely under the flushing rim and 85 terminating at its rear end entirely above the top plane of the flushing rim, as extended, with no part of its structure above said rim forward of point of seat attachment; and means for washing the exposed inner 90 surface of the vent duct.
8. In a water closet, the combination of a bowl; an underlying trap and siphon; a continuous flushing rim for the bowl; a vent duct of large area extending rearwardly 100 from the rear portion of the bowl, below the continuous flushing rim and above the trap and siphon, presenting a free, unobstructed and undiminished passage throughout its length, with no portion of the vent passage 105 or structure above the rim of the bowl forward of the seat attachment and entirely above said rim at its outlet; a water inlet above the vent duct; a jet opening from the water inlet through the upper wall of the 110 vent duct; a water conduit on either side of the closet leading from the inlet and terminating in a chamber having an actuating jet as its outlet; and a lateral conduit on either side of the closet entirely below the 115 rim and above the normal water level of the bowl leading from said jet chamber; conduits extending from said aforesaid water conduits to the flushing rim and feeding the same from below on either side of the closet 120 at a point forward of the rear segment of the rim.

In testimony whereof I have signed my name to this specification..

WINFIELD E. HINSDALE.
